(57) **CLAIM**

The ornamental design for a slipper, as shown and described.

DESCRIPTION

FIG. 1 is a top perspective view of a slipper showing my new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a bottom plan view thereof;

FIG. 8 is a top plan view thereof; and,

FIG. 9 is an enlarged view of portion 9 marked in FIG. 2. The dash-dot-dash broken lines in the drawings depict boundaries of the enlargement that form no part of the claimed design.

1 Claim, 9 Drawing Sheets
